INTERNAL COMBUSTION ENGINE

Victor F. Zahediakian, Cincinnati, Ohio

Application August 31, 1933, Serial No. 687,659

3 Claims. (CL 123—79)

The invention relates to improvements in internal combustion engines and is particularly directed to the construction of the exhaust valves thereof.

5 The objects of the invention are to provide simple, efficient and practical means whereby pressure in the combustion chamber of the engine does not affect or tend to affect opening or closing of the exhaust valve; to provide simple and efficient means adapted to maintain the exhaust valve at a low temperature, as by passage of fuel charges and also as by provision of means to shield the exhaust valve head from contact by the exhaust fuel gases; and to provide means adapted to shield the exhaust valve guide, in which the exhaust valve is slidably mounted, from contact with the exhaust fuel gases.

10 The invention consists in the combination of the elements, arrangement of the parts and in the details of the construction, as hereinafter fully described and claimed.

In the drawings:

15 Fig. 1 is a central vertical section, with parts broken away, taken through an internal combustion engine, showing the exhaust and intake valves in closed position;

20 Fig. 2 is the same showing in full lines the exhaust valves in open position and showing the intake valve in closed position and showing in dotted lines the exhaust valve in closed position and the intake valve in open position;

25 Fig. 3 is a vertical section showing a modified form of the rocker arm; and—

30 Fig. 4 is a plan elevational view of the rocker arm plunger.

35 In the preferred construction of the invention I provide the internal combustion engine 1 comprising the block 2 having suitably secured to its top the engine head 3. In the engine block 2 is the cylinder 4 having therein the reciprocating piston 5 having the grooves 6 circumferentially of the top 7 for receiving the usual piston rings 8 for the purpose of preventing escape of compressed gases from the combustion chamber 9 downwardly between the cylinder walls and the piston. Suitably secured in the sides of the piston 5 is the usual wrist pin 10 having rotatably mounted thereon the usual connecting rod 11 which is connected with the usual crank shaft (not shown).

40 The top wall of the piston is relatively thin. Centrally disposed of the top 7 of the piston 5 is the electrode 13 having its top 14 projecting

upwardly from the top surface of the piston. The lower end 15 of the electrode 13 projects downwardly into the interior 12 of the piston.

45 Secured to the upper surface of the engine head 3 is the valve housing 16. The lower edge of the valve housing has the inwardly extending flange 17 through which is received the bolt 18 which is received through the flange 17 and into the engine head.

50 The upper end of the valve housing 16 is U-shaped having the chamber 19 therein which communicates with the chamber 20 formed by the spaced apart walls 21 and 22 of the top 23 of the pressure guide or casing 24. The top 23 of the guide 24 is curved outwardly and the chamber 20 communicates with the chamber 19 in the valve housing which communicates with the usual inlet 25 through which the intake fuel charge passes.

55 The engine head 3 is provided with the bore 26 which is in axial alignment with the cylindrical bore 4 in the block. The bore 26 is relatively smaller in diameter than the cylinder 4. The inner walls 27 of the head 3 are inclined downwardly and outwardly and their lower edge 28 is aligned with the walls 29 of the cylinder.

60 The vertical tubular downwardly extending body 30, integral with the wall 22 of the guide 24, has therein a circular chamber 31 in which is disposed the vertical tubular valve guide support 32 integral with the walls 21 of the pressure housing or guide top 24. The tubular support 32 has axially disposed therein the valve guide 33 having the bore 33' in which is slidably mounted 35 the intake valve 34.

65 Received in the downwardly disposed cup portion 35 of the spring retainer 36 is the upper end 37 of the intake coil spring 38 which has its lower end 39 received on the shoulder 40 centrally disposed of the top 23 of the pressure housing 24, and in the depression formed by the upwardly and outwardly curved walls 21. The coil spring 38 surrounds the upper end of the intake valve guide 33. The valve guide has 45 integrally formed therewith the outwardly extending flange 41 which is supported by the shoulder 40.

70 The lower ends 42 and 43, respectively, of the support 32 and the guide 33 are substantially 50 aligned horizontally. The intake valve stem 44, of the valve 34, has integrally formed with its lower end the intake valve head 45. During the intake stroke of the piston 5 the intake valve head 45 is in open position, whereas during the 55

compression, explosion and exhaust strokes of the piston the valve head 45 contacts its seat 46 formed at the lower end of the body 30. The desired movement of the intake valve 34 is supplied by contact of the inner end 47 of the rocker arm 48 therewith which forces the valve 34 into open position during the intake stroke of the piston, whereas during the compression, explosion and exhaust strokes of the piston 5 the end 47 of the 5 rocker arm 48 is moved to an upward position which permits the intake valve coil spring 38 to exert upward pressure against the spring retainer 36, thereby imparting upward movement to the valve which forces the valve head 45 into 10 contact with its seat 46.

In the upper end 49 of the valve stem is the annular groove 50 into which is fitted the split washer 51 having its outer side inclined inwardly and downwardly and being received in the centrally disposed bore 52 in the spring retainer, whereby the spring retainer is retained in fixed 20 position with respect to vertical movement on the valve stem.

The hollow horizontal intake valve rocker shaft 25 53, which extends longitudinally above the engine head 3, is mounted in the bearing 54 of the upwardly extending support lug 55 which is integrally formed with the top 23 of the pressure guide 24.

30 The rocker arm 48 is rotatably mounted on the shaft 53 and has in its rear end 56 the threaded bore 57 into which is threaded the bolt 58, the lower end of which is contacted by the push rod 59 which is slidably in the boss 60 of the bracket 61 integral with the housing 16. The lower end of the rod 59 is in contact with the intake cam 62 which is parallel to the exhaust cam 63, both cams being fixed to the cam shaft 64. Suitable means are provided for connecting 35 the cam shaft with the usual crank shaft (not shown) of the engine for the purpose of rotating the cam shaft.

35 The exhaust rocker arm shaft 65 is suitably mounted on the engine head and has rotatably 45 mounted thereon the exhaust rocker arm 66 the end of which 67 has the bore 68 therein in which is threaded the bolt 69 the end of which 70 is adapted to contact the lower end of the push rod 71 which is slidably mounted in the bore 72 50 in the boss 73 integrally formed with the lower portion of the bracket 61. The inner end 74 of the rocker arm is adapted, when the push rod 71 is actuated by the exhaust cam 63, to be forced upwardly by contact of the push rod 71 with the bolt 69 which imparts downward movement to the outer end 67 of the rocker arm. The end 74 55 of the rocker arm is engaged against the flange 75 of the collar 76 which is threaded to the upper portion of the stem 77 of the exhaust valve 78. The exhaust valve 78 is mounted around the lower portion of the body portion 30 and within 60 the exhaust valve guide 79 which is received in the bore 80, in the engine head, directly above the cylinder. The outwardly extending flange 81, integrally formed with the upper end of the valve 65 guide 79, is suitably secured to the engine head.

65 Received around the upper end of the valve support 24 is the coil spring 82 which has its upper end 83 in contact with the upper end of the wall 22, of the guide 24. The lower end 84 of the spring is received in the depression 85 in the flange 75 of the collar 76 whereby the compression in the spring 82 is adapted to exert downward force on the exhaust valve for the purpose 70 of causing the exhaust valve head 86 to contact

its seat 87, which is formed in the engine head 3 adjacent the port 28.

In the center of the stem of the intake valve 34 is the bore 88 in which is received the insulation 89 having the bore 90 therein in which is received the electrode 91 having its upper end projecting outwardly from the upper end of the insulation and spaced a slight distance from the lower end 92 of the electrode 93 which has the outwardly extending flange 94 integrally formed 10 with its body 95. The flange 94 is contained in the hole 96 in the insulation 91. The insulation is formed about the flange and within the plug 98 having its lower end threaded in the hole 96 in the top 100 of the cover 101. The cover is suitably retained in fixed position by the bolt 102 which is screwed into the support 55. A suitable conductor (not shown) may be connected with the upper end 103 of the electrode 93. This conductor may be suitably connected with suitable 20 outside source of electric supply for the purpose of supplying electric current for the purposes hereinafter fully explained.

25 Projecting from the lower end of the insulation is the lower end of the electrode 91 which 25 is positioned centrally and above the piston 5 and in vertical alignment with the electrode 14.

The inner surfaces of the exhaust valve head 86 and the exhaust valve stem 77 are in vertical alignment. The inner surface of the walls of 30 the exhaust valve are substantially parallel with the walls 29 of the cylinder 4, or at least a line extended downwardly from the inner surface of the exhaust valve walls would be parallel with the inner walls of the cylinder. The exhaust 35 valve, inlet valve, valve guides or supports are concentric and are coaxial with the cylinder bore, and valve seats.

The walls of the exhaust valve seat 87 are inclined downwardly and inwardly and the lower 40 end of the open exhaust valve head 86 is also inclined downwardly and inwardly in substantial parallel relation with the walls of the exhaust valve seat. When the exhaust cam 63 is not actuating the push rod 71 and the end 74 of the 45 rocker arm 66 is permitted to move into its downward position, as shown in Fig. 1, the coil spring 82 exerts downward force in contact with the collar 76 which imparts downward movement to the exhaust valve whereby the exhaust valve head 86 50 contacts its seat and thereby closes the outlet 110, which leads from the combustion chamber 9 outwardly of the engine head 3, whereby during the intake, compression and explosion strokes of the piston 5 the exhaust outlet 110 is closed. 55

The intake valve head 45 remains in contact with its seat during the compression, explosion and exhaust strokes of the piston 5 for the purpose of preventing passage of burned fuel gases from the combustion chamber 9 into the chamber 31 of the body 30. During these periods the intake cam 62 is not active on the lower end of the rod 59 whereby the end 47 of the rocker arm 48 is permitted to be in its uppermost position. However during the intake stroke of the piston 65 5 the cam 62 actuates the push rod 59 whereby the end 56 of the rocker arm 48 is elevated upwardly thereby causing the end 47 of the rocker arm to act against the upper end of the intake valve stem thereby forcing the stem downwardly. The intake valve head 45 is moved from its seat 46 to permit the fuel charge to pass from the inlet 25 25 through the chambers 19, 20 and 31 to the combustion chamber 9.

Just prior to the beginning of the exhaust stroke 75

of the piston 5 the exhaust cam 93 actuates the push rod 71, thereby forcing the end 67 of the rocker arm 66 downwardly, whereby the inner end 14 of the rocker arm is caused to move upwardly against the collar 76 for the purpose of elevating the exhaust valve from contact with its seat, and the burned fuel gases are permitted to be forced from the combustion chamber 9, through the bore 26, into the exhaust outlet 110.

Just prior to the explosion stroke of the piston 5, and immediately after the compression stroke of the piston, electrical current is received by the electrode 91 whereby a spark is adapted to jump the gap between the electrode and the upper end 14 of the electrode 91 and the electrical current continues downwardly through the electrode. When the piston 5 has reached its uppermost position the upper end 14 of the electrode 91 is properly spaced with respect to the lower end of the electrode 91, whereby a spark is permitted to jump the gap, between the upper and lower ends of the electrodes 14 and 91, respectively, thereby igniting the compressed charge of fuel within the combustion chamber 9.

The inner surface of the exhaust valve head 86 is aligned with the inner surface 105 of the engine head 3. Therefore, the compression within the combustion chamber has no effect in causing opening or closing movements of the exhaust valve. Also, the lower end 106 of the exhaust valve guide 79 has its inner surface inclined downwardly and outwardly, whereby a space 107 is left between the stem 77 of the exhaust valve 78 and the lower end of the guide 79, when the valve 78 is in downward or seated position as shown in Fig. 1. When the valve 78 is in its open position, as shown in Fig. 2, the downwardly and outwardly curved outer surface, or heel 108 of the exhaust valve head 86, fits the contour of the inner surface of the lower end of the valve guide 79 whereby only the contact or seating surface 109 of the exhaust valve head 86 is exposed to contact of the burned fuel gases which escape from the chamber 9 into the outlet passageway 110 in the engine head 3. Therefore, since the heel 108 shields the exhaust valve stem 77, of the exhaust valve, against contact by the heated exhaust gases, the stem 77 is adapted to remain relatively cool during operation of the engine, particularly because the inlet charge passes in contact with the inner surface of the lower end of the exhaust valve, thereby reducing its temperature.

In Fig. 3 there is shown a modified rocker arm 111, which may be substituted for either the exhaust rocker arm 66 or the intake rocker arm 53, shown in Fig. 1.

The rocker arm 111 has the bushing 112 in its bearing which is mounted on the shaft 113 which has therethrough a bore 113'. The aperture 114 in its side wall communicates with the bore 113' and registers with the aperture 115 in the bushing 112. The aperture 115 communicates with the passageway 116 in the rear or outer end 117 of the rocker arm. The passageway 116 communicates with the passageway 118, which is formed in the rear end of the rocker arm, and has therein the coil spring 119 the inner end of which contacts the ball 120 which is adapted to contact its seat formed between the passageways 116 and 118 to prevent escape of oil which may be in the passageway 118. The other end of the coil spring contacts the pin 121 which is screwed into the rocker arm. Formed at the outer end of the rock-

er arm is a boss 122 having therethrough the passage 123 in the lower end of which is screwed the plug 124. Between the plug 124 and lower portion of the outer end of the rocker arm are a plurality of plates 125 which may be removed from or added to for the purpose of adjusting the plug with respect to the plunger 126, which is slidable in the passage 123, so that the clearance can be provided permitting contact in event of failure of oil pressure normally developed by the engine oil pump (not shown) which by suitable means supplies oil under pressure to the bore 113' in the shaft 113. The passageway 118, in the rear outer end of the rocker arm, communicates with the apertures 128 and circular groove 129 in the plunger. The apertures 128 communicate with the bore 130 of the plunger 126. The plug 131 in the aperture 132 in the side wall of the boss 122, prevents escape of oil from the bore 130. The aperture 132 permits entrance of a drill into the rear end of the arm for drilling the passageway 118.

An advantage of the invention is that the arrangement and construction of the exhaust valve is such that the rocker arm 66 and the coil spring 25 are depended upon entirely to effect upward and downward movement, respectively, of the exhaust valve.

Another advantage of the invention is that the piston 5 is hollow whereby the oil within the piston, and which is supplied from the crank case of the engine, is adapted to maintain the top 7 of the piston relatively cool which results in the electrode 91 being maintained at a low temperature.

Still another important feature of the invention is that the spark caused by the close proximity of the electrode 91 with the lower end of the electrode 91 results in the compressed charge of fuel within the combustion chamber 9 being ignited immediately above the center of the top of the piston, whereby the ignition of the fuel charges travels rapidly from the center of the combustion chamber outwardly toward the walls of the cylinder, and rapid flame propagation is obtained.

Still another advantage of the invention is that the construction and arrangement of the exhaust valve and the associated elements is such that the valve is adapted to remain relatively cool.

While I believe that the form of the invention illustrated in the drawings and referred to in the above description, as the preferred embodiment, is efficient and practicable, yet realizing that the conditions concurrent with the adoption of the device will necessarily vary, I desire to emphasize the fact that changes in the details may be resorted to, when required, without sacrificing any of the advantages of the invention as defined in the claims.

Various changes may be made in the general form and arrangement of mechanical parts described without departing from the invention. Hence I do not limit myself to the precise details of the materials or the size and shape thereof as set forth, but consider myself at liberty to make such changes and alterations as fairly fall within the spirit and scope of the appended and final claims.

As to certain of the details which may be shown and not claimed in the present application, reference may be had to applicant's co-pending application Serial Number 687,658 and Patent No. 1,998,601, April 23, 1934, both of which were

filed on August 31, 1933, and entitled "Internal combustion engines."

What I claim as new and desire to secure by Letters Patent is:

- 5 1. In an internal combustion engine, an engine body including a head and cylinder block, said head including a bore coaxially disposed relative to the cylinder of said block, said head including a lateral exhaust passageway from said bore, a tubular exhaust valve and an inlet valve concentrically disposed and mounted in said bore, said exhaust valve surrounding said inlet valve, a tubular internal guide for said exhaust valve providing a seat at its lower end for said inlet valve, and a passageway therethrough for gas flow to the top of the cylinder, said exhaust valve extending across said exhaust passageway, said bore including a downwardly inwardly inclined seat, said exhaust valve head having an inclined contracting surface fitting said seat, the inner surface of said tubular exhaust valve disposed flush with the surface of the bore adjacent to and below the exhaust valve seat, means for independently actuating said valves, and a tubular guide externally surrounding said tubular exhaust valve and extended across a portion of the exhaust passageway for completely covering and shielding said exhaust valve from the hot exhaust gases, with the exception of the seating surface thereof, when the exhaust valve is open.
- 10 2. In an internal combustion engine, an engine body including a head and cylinder block, said head including a bore coaxially disposed relative to the cylinder of said block, said head including a lateral exhaust passageway from said bore, a tubular exhaust valve and an inlet valve concentrically disposed and mounted in said bore, said
- 15 3. In an internal combustion engine, an engine body including a head and cylinder block, said head including a bore coaxially disposed relative to the cylinder of said block, said head including an exhaust passageway extending laterally from said bore, a tubular valve support coaxially disposed relative to said bore, an inlet valve concentrically mounted in said support and including a head seated on the lower end thereof, said support constituting a gas inlet passageway, a tubular exhaust valve slidably mounted on said support, an external guide in said head mounting said exhaust valve, said bore including a seat for said exhaust valve below said lateral exhaust passageway, said external guide having an outwardly flared inner surface at its lower end, and said exhaust valve having an outwardly flared outer surface at the head end thereof corresponding to said flared surface of the guide, whereby the head end of the exhaust valve may be completely covered when the valve is open with the exception of the contacting surface of the exhaust valve.

VICTOR F. ZAHODIAKIN.
